METHOD OF PREPARING VAMPS FOR SHOES
OF THE CALIFORNIA OR FORCE-LASTED
TYPEWilliam F. Herlihy, Haverhill, Mass., assignor to
Lowell Counter Company, Lowell, Mass., a co-
partnership

Application April 8, 1950, Serial No. 154,776

3 Claims. (Cl. 12—142)

1

This invention pertains to the manufacture of footwear of the so-called "California" or "force-lasted" type and relates to a novel method of making such shoes and to a novel stage product resultant from the practice of said product, the present invention constituting an improvement upon that disclosed in the copending application for Letters Patent Serial No. 109,365, filed August 9, 1949, by William F. Herlihy, since issued as Patent No. 2,514,057, dated July 4, 1950.

The method disclosed in the aforesaid copending application comprises assembling a moldable stiffener blank with an end portion of the shoe upper, adhesively bonding the toe-box blank and upper material while molding said end portion of the upper, including the stiffener blank, substantially to the shape of said end portion of the shoe to be made, and after molding, uniting a wrapper strip to the lower margin of the upper by stitches which pass through the wrapper strip, upper and stiffener material. While the above method is highly desirable and is in daily use in the manufacture of shoes, it is most successful when the upper stock is thin and readily amenable to molding by direct pressure between dies. However, particularly when the upper stock is thick or stiff, the usual molding operation may tend to produce permanent pleats or gathers particularly at the upper material around the margin of the toe; these pleats or gathers extending up far enough to be visible in the completed shoe just above the wrapper, thus detracting from the appearance of the shoe and distinguishing it from shoes made by the conventional pulling over and lasting machinery.

The present invention has for its principal object the provision of a novel method whereby the disadvantages of the prior method, when applied to heavy or stiff upper material, are avoided and to the provision of an upper ready for attachment to the wrapper, having an included molded toe-box but which is devoid of pleats or wrinkles at the toe tip. A further object is to provide a California type shoe having a stiff toe-box and having the tip portion of the upper smooth and devoid of wrinkles or gathers adjacent to the wrapper. A further object is to provide a method of making a California or force lasted shoe whose toe end may have the stiffness and shape-retaining characteristics found in shoes of other types, but which is as smooth and devoid of wrinkles or creases as the stiffened tip of a shoe made by methods involving conventional pulling-over procedures. Other objects and advantages of the invention will be pointed out in the following,

2

more detailed description and by reference to the accompanying drawings wherein

Fig. 1 is a side elevation of a shoe upper prepared in accordance with the present invention and ready for the attachment of the wrapper;

Fig. 2 is a plan view of the quarter portion of the shoe of Fig. 1 before the assembly of other parts, viewed from the rear or outside;

Fig. 3 is a view similar to Fig. 2 but showing the inside of the quarter with a portion of the counter lining broken away;

Fig. 4 is a plan view of the vam of the shoe as it appears prior to the practice of the present invention;

Fig. 5 is a perspective view of the vam with the inner surface of the vam uppermost, showing the edge of the toe portion of the blank as having been shrunken to decrease its length;

Fig. 6 is a fragmentary, vertical section on the line 6—6 of Fig. 5;

Fig. 7 is a diagrammatic front view illustrating the step of molding the toe portion of the upper;

Fig. 8 is a vertical, central section substantially on the line 8—8 of Fig. 7;

Fig. 9 is a section similar to Fig. 6, but showing the toe end of the upper, including the toe box, as it appears at the completion of the molding operation;

Fig. 10 is a fragmentary, vertical section 30 through the toe end of the molded upper, illustrating the step of attaching the wrapper strip;

Fig. 11 is a similar view illustrating the step of attaching the sock lining; and

Fig. 12 is a side elevation of the completed shoe.

Referring to the drawings, the numeral 1 designates a shoe upper which may be of any desired material and pattern or style, and which, except as hereinafter specifically pointed out, may be of conventional construction. As illustrated, it comprises the quarter portion 2 and the vam portion 3, these parts being united by seams S. The vam 3 (Fig. 4) may be unlined or, if desired, provided with a liner (not shown). If a liner is used it would usually be united to the outer ply 45 of the vam by a seam extending over the arch of the toe tip, the liner being otherwise free. If a liner is used, the toe box blank hereinafter referred to will be inserted between the vam and the toe liner. If no liner is used, the toe box will be exposed at the inside of the shoe.

The quarter 2 (Figs. 2 and 3) comprises a blank including an outer ply which may be of leather, cloth or the like, the outer ply being here shown as provided with an external stay piece 55. As illustrated in Fig. 3, the upper edge of the

quarter is folded in and seamed, as shown at 7, to provide a finish bead. Except as hereinafter described the quarter is of single thickness but it is to be understood that it may comprise additional plies, for example, a complete lining. As here shown in Fig. 3, the quarter has a counter-lining 9 secured to the outer ply by a seam 10 which extends along the upper edge of the lining. The lower edge of this quarter or counter-lining is free from the outer ply, thus providing a 10 pocket for the reception of the stiffener or counterblank 12 (Fig. 3). This counterblank may be of any suitable material capable of being molded and of permanently retaining the shape imparted by molding pressure.

In accordance with the present invention, the vamp, which is here shown as unlined and consisting of a single thickness of material, for example leather, is subjected to an operation whereby its extreme lower edge 14 at the toe portion 13 is shrunken so that said extreme edge becomes less in peripheral length than the adjacent material of the vamp. This shrinking is carried out in such a way that the extreme edge portion 14 is thickened and becomes more dense. The result of this operation is to provide a pocket-like cavity 16 (Fig. 6) at the toe end of the vamp, the outer surface 15 of this pocket-like portion being convex and smooth and without visible wrinkles or corrugations. This operation of shrinking the margin of the toe end of the vamp may be performed by the use of a machine such as, for example, shown in the patent to Kamborian 2,378,639 dated June 19, 1945. However, the particular mode of shrinking this edge is not essential to the invention provided that the mode adopted results in the formation of the pocket-like cavity but without the creation of external pleats, corrugations or wrinkles of such size as to be visible in the completed shoe.

Having thus shrunken the edge of the toe portion of the vamp, the vamp has assembled with it a toe-box blank 17 (Fig. 9). This toe-box blank may be of any suitable material such as is employed for this purpose but should be capable of being molded and of permanently retaining the shape imparted by molding pressure. If initially too stiff for moulding, this toe-box blank may first be rendered soft and flabby by appropriate treatment such, for example, as mulling or treatment with appropriate solvents or the like, so that it may be fitted within the pocket 16 of the vamp and pressed firmly against the inner surface of the vamp. Unless the toe stiffener itself is inherently adhesive, adhesive A is introduced between the inner surface of the vamp and the toe stiffener as a preliminary to their assembly.

If desired, although it does not appear necessary except perhaps in extreme cases, the toe-box blank 17 may be subjected to a preliminary or partial shaping operation, for example by molding, so as to permit it to be fitted more closely within the pocket of the vamp prior to the next operation.

While a toe-box blank separate from the vamp proper is ordinarily employed, it is within the purview of the invention to employ a vamp whose toe portion is, itself, capable of taking and permanently retaining a shape imparted by molding pressure.

Having assembled the toe-box blank, if used, within the pocket 16 in the vamp, the toe portion of the vamp is now subjected to molding

pressure in a suitable molding machine, for example a machine of the kind commonly used for molding shoe counters. This operation, as employed in molding the toe portion of the vamp, is illustrated by way of example in Figs. 7 and 8. As shown, the toe end of the vamp, with its associated stiffener 17 is assembled about the center mold of the molding machine and when so assembled with the center mold it is embraced by the side molds 19 and 20 which are shaped appropriately to impart to the toe portion of the vamp a final curved contour such as it is desired that it have in the completed shoe, it being understood as above suggested, that the stiffener element is of a character to retain this molded shape indefinitely. The quarter or counter portion of the shoe may likewise be formed in accordance with the present invention except that the edge shrinking step is unnecessary. Thus, 20 after the stiffener or counter member 12 has been assembled with the quarter, the assembly will be subjected to a molding operation in a molding machine having dies appropriately shaped to impart to the quarter of the shoe its final shape. 25 While it has been suggested that the vamp and quarter will be united by the seams S prior to the molding of either end of the upper, it is contemplated that the molding may take place prior to the union of the vamp and quarter. 30 Furthermore, if the shoe is to be of the open shank type, the vamp and/or quarter may be molded independently as above suggested and will not subsequently be united by seams S or the equivalent, but will be independently anchored to the bottom structure of the shoe. It is thus contemplated, as within the scope of the present invention, to make the vamp and quarter portions independently in accordance with the present invention and that such parts may be made 35 and molded and, whether or not united, further completed to the extent that they might be sold as stage products useful in the manufacture of California type shoes.

Referring more particularly to the completion 45 of the toe portion of the upper after it has been given its shape and contour by the edge shrinking and molding operations above described, a wrapper strip 21 of appropriate width and material is now stitched to the lower marginal portion 50 of the molded vamp by a seam whose stitches 22 pass through all of the constituent plies of the vamp, including the outer ply, the toebox and the lining, if there be a lining. This operation may be carried out by the use of any suitable type 55 of sewing machine. In spite of the premolding of the end portion of the shoe, a flat bed machine may be used for the purpose without particular difficulty.

If the upper has been molded at both ends and 60 if the quarter and vamp have been united by the seams S, the wrapper 21 may extend continuously around the entire periphery of the shoe upper, except that usually the ends of the wrapper will be overlapped at approximately the location of the seam S at the inner side of the shoe. 65 If the quarter and vamp are made as separate entities, each will be provided with its own independent wrapper strip, the ends of each wrapper strip being located approximately at the rear and forward ends of the parts 3 and 2, respectively.

Having thus attached the wrapper strip or strips, the sock lining 23 (Fig. 11) is now assembled with the upper or with one or the other 70 part of the upper as above described; its mar-

ginal portion is turned downwardly; and said marginal portion is united by a seam comprising stitches 24 which pass through all of the constituent plies of the upper, including the stiffener element at its molded end or ends. If the quarter and vamp are made as separate elements and not united by the seams S, then the sock lining forms the only connection between the parts 2 and 3 before the cushion and/or outer sole is applied.

A cushion sole or platform element is now usually secured in customary manner by adhesive or otherwise to the undersurface of the sock lining, and the lower margin of the wrapper strip 21 is turned down beneath the platform or cushion and adhesively secured to the latter. If a heel wedge is to be used, such a wedge is now put in place and adhesively united to the cushion element. The wedge here shown as an edge cover 25 (Fig. 12). In some types of shoes the wrapper strip 21 is not turned in directly below the cushion element but is of such dimensions, at the heel end of the shoe, that it may be turned in beneath the heel wedge, concealing the side edges of the latter. After the parts have been assembled and united, as above suggested, an outer sole is assembled with the other parts and attached in conventional manner.

While as above suggested, and as illustrated in the drawings, the wrapper strip is attached to the molded end portion of the shoe by a seam 22 which is above and separated from the seam 24 which unites the sock lining to the upper, it is contemplated that both wrapper and sock lining may be united simultaneously to the molded end portion of the shoe by the same seam. It is further contemplated that the sock lining may be attached to the molded upper prior to the attachment of the wrapper, if for any reason this should be desirable.

While the toe-box blank will usually be in flat condition when assembled with the vamp, it may be given a partial preliminary molding before assembly, as above suggested. Moreover, the stiffening element may be assembled with and adhesively united to the vamp while the latter is in flat condition, and then the assembled parts may be subjected to the shrinking operation so that the edges of both vamp and stiffener will be shrunken concomitantly.

By the above procedure it is possible to provide a California type shoe having a permanently stiff and properly shaped end portion wherein the stiffener element is firmly and securely united to the other parts, the outer surface of the toe being smooth and free from wrinkles or pleats as that of a shoe made by other conventional methods involving a pulling-over operation, the stiffened end portion of the upper being anchored just as firmly in place to the bottom structure as in other forms of shoe.

While one desirable procedure has been suggested and illustrated by way of example, it is to be understood that the invention is broadly in-

clusive of any and all modifications and variations in the several steps and order of steps within the scope of the appended claims.

I claim:

1. A method of preparing vamps for shoes of the California or force-lasted type which comprises providing a vamp, providing a moldable toe box blank, forming a pocket in the toe portion of the vamp for the reception of the toe box blank by shrinking the extreme lower edge of the toe end of the vamp while leaving unshrunken the adjacent marginal material of the toe end of the vamp, placing the toe box blank in said pocket, adhesively bonding the toe box blank and vamp while concomitantly molding the toe box blank and the toe portion of the vamp by appropriately shaped dies substantially to the shape of the toe portion of the shoe which is to be made, and securing a wrapper strip and a sole element to the vamp after the latter has been molded.
2. In the method of preparing vamps according to claim 1, the further improvement which comprises the step of attaching the wrapper to the vamp, after the latter has been molded, by a seam whose stitches pass through all of the constituent plies of the vamp and the toe box blank.
3. A method of preparing a vamp for use in the manufacture of a shoe of the California or force-lasted type which comprises providing an upper, progressively shrinking the extreme lower edge of the upper at its toe end with resultant increase in density and thickness of the extreme edge while leaving the adjacent marginal material unshrunken thereby forming an externally smooth, outwardly convex pocket at the toe of the upper, providing a moldable toe box blank of a material which, after molding, will retain its molded shape, inserting the toe box blank within said pocket and with its lower edge registering with the lower edge of the pocket, adhesively bonding the toe portion of the upper and the toe box blank while concomitantly molding the assembled upper and blank substantially to the final shape of the toe portion of the shoe to be made, and after molding, uniting a wrapper strip to the lower margin of the upper by stitches which pass through the upper, wrapper and toe box material.

WILLIAM F. HERLIHY.
